UNITED STATES PATENT OFFICE

157,899

AUTOMOBILE TOP

William Poulos, Bridgeport, Conn.

Application July 27, 1948, Serial No. 147,797

Term of patent 14 years

(Cl. D14—27)

To all whom it may concern:

Be it known that I, William Poulos, a citizen of the United States, residing at Bridgeport, county of Fairfield, and State of Connecticut, have invented a new, original, and ornamental Design for an Automobile Top, of which the following is a specification, reference being had to the accompanying drawing, forming part thereof.

Figure 1 is a side view of an automobile top showing my new design; and

Fig. 2 is a back view thereof.

Fig. 3 is a top perspective view thereof.

The dotted lines shown in Figure 1 and Fig. 2 are for illustrative purposes only.

I claim:

The ornamental design for an automobile top, as shown and described.

WILLIAM POULOS.
